UNITED STATES PATENT OFFICE.

THEODORE E. SCHUMANN, OF NEW YORK, N. Y.

HEATING DEVICE.

Application filed December 17, 1926. Serial No. 155,539.

This invention relates to improvements in heating devices, having for an object to provide a device for heating the cooling medium of an internal combustion engine during cold or frigid weather to an extent or degree sufficient to prevent freezing of the medium about the engine without damage thereto or to those accessories employed in its cooling medium circulating system. It is also an object of the invention to provide a heating device of the character mentioned which can be installed upon an internal combustion engine without alteration or modification of the same and which, when functioning, will be fire proof and thus, avoid burning of the engine or of the vehicle propelled thereby.

Yet another object of the invention is to provide a burner for the device, the same being housed within said device and being of a construction such as will effect the production of an even and uniform heating flame of maximum degree throughout its length with but a minimum fuel consumption.

Other objects of the invention will be in part obvious and in part pointed out hereinafter.

In these drawings:

Figure 1 is a fragmentary side elevation of an internal combustion engine having the water supply pipe of the cooling medium circulating system thereof equipped with the invention,

Figure 2 is an enlarged side elevation of the improved heating device,

Figure 3 is a vertical transverse section taken upon the line 3—3 of Figure 2 looking in the direction in which the arrows point,

Figure 4 is a detail in side elevation of the burner employed in connection with this heating device;

Figure 5 is a top view of the same;

Figure 6 is a longitudinal section through the housing of the heating device, taken on the line 6—6 of Figure 2; looking in the direction in which the arrows point; and

Figure 7 is a vertical longitudinal section through the improved burner.

Having more particular reference to the drawings in connection with which like characters of reference will designate corresponding parts throughout, the improved heating device may be stated to comprise a

housing or casing of sheet metal generally designated by the numeral 1, the bottom, side and end walls of said housing being closed whereas the top of the same is open and the upper portions on the opposite side walls thereof are formed with outwardly extending right angularly disposed flanges 2, the intermediate portion of one of which carries upon its under side a block or plate 3 formed with a screw threaded opening corresponding with a similar opening formed in the adjacent portions of the corresponding flange 2; for a purpose which will be subsequently described.

The open top of the housing 1 is adapted to receive a cover plate 4 thereupon, said cover plate being of a length corresponding to the length of the housing 1 and having a longitudinally disposed pocket 5 formed throughout the same and adapted to be received within the opposite side and end walls of the upper portion of the housing in the manner shown in the Figure 3, one side of said top plate 4 being hingedly connected to the adjacent flange 2 as is indicated by the numeral 6, thus permitting the swinging of the longitudinally depressed pocket 5 from without the open upper end of the housing 1, whereby access may be had to the interior of the same. That the top plate 4 may be secured in its closed position with respect to the open upper end of the housing 1, a locking screw 7 is passed through an intermediately arranged opening in the free side of said plate and this locking screw is adapted to be turned into engagement with the screw threaded opening formed in the plate 3, hereinbefore described. Thus, it will be understood that the top 4 may be secured in its closed position with respect to the open upper end of the housing 1, as may be required.

With a view toward providing the device with means for attaching or securing the same to the water supply pipe 8 of the cooling system of an internal combustion engine, I provide a plurality of metal hanger straps 9, forming openings in the opposite extremities thereof adapted to be aligned with corresponding openings in the opposite side portions of the top plate 4, whereupon securing bolts and nuts 10 are passed through said opposite sides of the top plate 4 and the opposite extremities of the straps 9; hence, effecting a positive connection of the latter

to the former. Before engaging the bolts and nuts 10 in the manner described, it will be understood that the lower portion of the water supply pipe 8 of the cooling medium circulating system of the equipped internal combustion engine is arranged in a longitudinally disposed and depressed pocket 5 in said top plate 4, whereupon the hanger straps 9 are engaged over the upper portion 10 of said pipe 8 in the manner shown in the Figure 1, following which the bolts and nuts 10 are then engaged so as to effect a supporting or attaching connection of the heating device to the underside of said pipe 8.

15 A longitudinally disposed fuel conveying pipe 11 is extended throughout the length of the bottom of the housing 1 and, as shown in the Figure 6, has the upper side thereof cut away as indicated at 12 while a plurality 20 of equi-spaced openings or perforations 13 are formed in the bottom thereof, in order that the particular fuel employed in connection with the heater may be discharged into said bottom of the housing 1 and evenly 25 distributed throughout its length for supply to the burner, hereinafter more fully described. The bottom portion of the housing 1, preferably, is provided with a layer of 30 absorbent material, such as raw cotton or the like, designated by the numeral 14, such material being arranged closely about the fuel supply pipe 11 and thus serving to receive and evenly absorb and distribute the inflow of fuel to the device, in order that its 35 even distribution to the burner will be insured.

Also, the upper portions of the opposite side walls of the housing 1 are formed with a plurality of relatively spaced air admitting 40 openings or ports generally designated by the numeral 15, whereas larger openings 16 are formed intermediately of the aforesaid opening and obviously serve to permit of ready ignition of the burner within the 45 device when desired; likewise, to allow of inspection of the burner or the flame produced therealong.

The burner of my improved heating device may be stated to comprise a body portion 50 constructed of sheet metal or other suitable material, corresponding to that from which the housing 1 is constructed, said body including opposite sides 17 formed with oppositely disposed supporting feet 18, while 55 bands or cross pieces 19 span the opposite ends of the burner body and, obviously, serve to effect proper relative spacing of the opposite sides 17. The upper or top portion 60 of the burner body is reduced by bending the upper portions of the opposite side walls 17 thereof inwardly as shown at 20 and then forming inturned flanges 21 upon the same, the intermediate portions of the inwardly 65 disposed guards 20 of the burner being formed with series of equi-spaced openings

generally indicated by the numeral 22, whereby a proper supply of oxygen to the heating flame will be insured.

The upper portions of the side walls 17 of the burner are maintained in rigid relative spaced relation by the insertion of transversely disposed bracing pins 23, the opposite ends of which are reduced and received in equi-spaced openings or perforations 24 formed in upper portions of said walls 17 75 below the aforesaid oxygen admitting openings 22. Thus, it will be understood that inward flexing or bending movement of the upper portions of the walls 17 or contraction of the same by reason of the application of high temperatures thereto will be prevented and consequently effectual functioning of the burner will at all times be insured. In this connection, it is to be noted that the length and width of the burner is such as to permit of the snug reception within the heater casing 1, as is indicated in the Figure 3.

The lower portion of the burner body is adapted to be supplied with a quantity of 90 absorbent material, such as raw cotton or the like, designated by the numeral 25, this packing or filling being extended upwardly between the side walls 17 to a point immediately below the perforations 24, whereupon the longitudinally disposed screen 26 is arranged over the same and beneath the cross pins 23, aforesaid, as is clearly shown in the Figures 3 and 7. Another longitudinally disposed screen 27 is arranged in the 95 upper portion of the burner body between the opposite side walls 17 thereof, the opposite sides of this particular screen being joined or fixedly connected to adjacent portions of the inwardly bent parts 20 of said 100 walls 17, thus providing a chamber or pocket immediately above said screen 27 in which fibrous asbestos or similar matter 28 is packed, said matter 28 being arranged so as to lie substantially flush with the open upper 110 surface of the flanged portions 21 of the reduced or inwardly disposed sides 20 and being held against displacement with respect thereto through the medium of a plurality of relatively spaced ties or wires 29, the 115 opposite ends of which are bent upon themselves and engaged in adjacent openings 22. By positioning or arrangement of the asbestos fibre 28 within the reduced upper portion of the burner body, it will be understood that a chamber will be effected as between the upper portion of the absorbent material 25 and said asbestos fibre 28, whereby to insure the conversion of the liquid fuel employed in the heating device into a highly combustible gas having air admixed therewith in proper proportion for sustaining perfect combustion along and throughout the length of the asbestos fibre 28.

To permit of placement or removal of the 130

burner in or from the casing 1 of the heating device, a bale like handle 30 is provided, one portion of said handle being bent upon itself as indicated at 31 and having 5 trunnions formed upon the free extremity thereof and engaged in the adjacent perforations 22, as is shown in the Figures 4 and 5. Thus, the handle 30 may be swung upwardly so as to permit of dropping of 10 the burner into the casing 1 whereupon said handle may be then swung downwardly over adjacent portions of the end wall of said housing and the handle thus arranged without the housing and accessible at all times, 15 as may be required.

The supply pipe 11 may be and preferably is provided with a union or nipple 32 adapted to be connected to a supply pipe or corresponding coupling upon a suitable 20 liquid fuel reservoir 33 arranged at an appropriate or convenient place upon the engine equipped vehicle.

In operation of my improved heating device and assuming that the same is connected to the under side of the water return pipe 8 of the cooling medium circulating system in the manner hereinbefore described, fuel is discharged by way of the supply pipe 11 into the bottom of the casing 1 having 25 the layer of absorbent material 14 therein. This fuel in turn is taken by capillary attraction upwardly to the absorbent material 25 throughout the entire length of the burner and during such passage is converted 30 into a highly combustible gas, which in turn is delivered through the mesh of the screens 26 and 27 to the asbestos fibre 28 arranged flush with the open upper side of the reduced top portion of the burner 20, whereat the 35 same is ignited and burned throughout the entire length of the burner, directing a heating flame onto the under side of the top plate 4 having the longitudinally disposed and depressed pocket 5 therein and in which the under side of the water supply pipe 8 of 40 the cooling medium circulating system is arranged. In this way, it will be understood that the water or other cooling medium passing through the water supply pipe 8 of the circulating system will be maintained 45 at a temperature such as will prevent freezing, with the resultant damage of the engine or of those accessories employed in the circulating system, as well as bringing about 50 material inconvenience to the operator of the engine equipped vehicle.

The heating flame produced by the burner may, of course, be regulated to the desired 55 nicety by suitable control of the supply of fuel to the supply pipe 11 through a valve or other suitable device (not shown) interposed in the fuel supply line.

By reason of the removable arrangement 60 of the burner within the housing 1, it will 65 be understood that the active parts of my

improved heating device may be readily disassembled for cleaning, repair or other purpose that may be required and likewise, by reason of this convenient arrangement of parts, the heating device may be installed 70 upon an internal combustion engine in but a minimum amount of time and by unskilled labor.

Manifestly, the construction shown is capable of considerable modification, and such 75 modification as is within the spirit of my claims, I consider within the scope of my invention.

I claim:

1. A heating device for the cooling system 80 of internal combustion engines comprising a casing; a fuel supply member extending throughout the lower portion of the casing; fuel receiving and distributing means arranged about said fuel supply means; and 85 a burner body having fixed therein a fuel absorbent conducting means, contacting with said fuel supply member and said fuel receiving and distributing means whereby through capillary attraction said absorbent 90 conducting means will evenly absorb the inflowing fuel.

2. A heating device for the cooling system 95 of internal combustion engines comprising a casing; a fuel supply means extending throughout the lower portion of the casing; a fuel receiving and distributing material arranged about said fuel supply means; and, a burner body having porous and fuel conducting material, said materials being spaced 100 to provide an air circulating chamber therebetween, whereby to effect the conversion of liquid gas into highly combustible gas.

3. A heating device for the cooling system 105 of internal combustion engines, comprising a casing; a fuel supply pipe extending throughout the lower portion of the casing, said pipe having a longitudinal opening throughout its top portion and a series of apertures longitudinally disposed and relatively spaced throughout its bottom portion; a receiving and distributing material arranged closely about said pipe communicating with the apertures in the bottom portion thereof; and a burner body received 110 within the casing, a portion of said burner body having absorbent conducting means contacting with the longitudinal opening in the top portion of the fuel supply pipe and with the receiving and distributing material 115 surrounding the same, whereby through capillary attraction, the inflowing fuel will be evenly absorbed by said absorbent conducting means.

4. A heating device for the cooling system 125 of internal combustion engines comprising a casing having a series of air admitting holes longitudinally disposed in the upper side portions thereof; a fuel supply pipe extending within and throughout the 130

lower portion of the casing; a receiving and distributing material arranged closely about said pipe; and, a burner body having porous material in its upper portion and absorbent 5 conducting material in its lower portion, said porous material and absorbent conducting material being spaced providing therebetween an air circulating space communicating with the air admitting holes in the casing whereby to effect the conversion of liquid 10 gas absorbed by the absorbent conducting material into a highly combustible gas.

5. A heating device for the cooling system of internal combustion engines comprising 15 a casing having a series of air admitting holes in the upper side portions thereof; a fuel supply pipe extending within the lower portion of the casing and having a longitudinal opening throughout its top portion 20 and a plurality of apertures throughout its bottom portion, receiving and distributing means arranged about the fuel supply pipe and communicating with the apertures in the bottom thereof, and a burner body hav-

ing a porous material in its top portion and 25 a fuel absorbent conducting material in its lower portion, said absorbent conducting material contacting with the fuel supply pipe and the receiving and distributing means to evenly absorb the fuel therefrom 30 and being spaced away from the porous material providing an air circulating space communicating with the air admitting holes in the casing, whereby said fuel will be changed into high combustion gas for consumption by the porous material.

6. A device of the character described comprising a casing having air ports and fuel supply means therein, and a burner body received in said casing and including a 40 porous material communicating with said air ports and a fuel absorbent conducting material spaced from said porous material and contacting with the fuel supply means.

In witness whereof I have hereunto set 45 my hand.

THEODORE E. SCHUMANN.
